CLAIM

The ornamental design for a single outlet template, as shown and described.

DESCRIPTION

FIG. 1 is a perspective view of the single outlet template with environment;

FIG. 2 is a perspective view of my design;

FIG. 3 is a front view of my design;

FIG. 4 is a rear view of my design;

FIG. 5 is a top view of my design; and,

FIG. 6 is a side view of my design.

The broken lines depict environmental structures of the bottle and sprayer and form no part of the claimed invention.
